(57) **CLAIM**

The ornamental design for a battery, as shown and described.

DESCRIPTION

FIG. 1 is a front, top, and left side perspective view of a battery showing our new design;
FIG. 2 is a rear, top, and right side perspective view thereof;
FIG. 3 is a rear, bottom, and right side perspective view thereof;
FIG. 4 is a front, bottom, and left side perspective view thereof;
FIG. 5 is an enlarged detail view of a front and left side perspective view thereof;
FIG. 6 is a front elevational view thereof;
FIG. 7 is a rear elevational view thereof;
FIG. 8 is a left side elevational view thereof;
FIG. 9 is a right side elevational view thereof;
FIG. 10 is a top plan view thereof; and,
FIG. 11 is a bottom plan view thereof.
The broken lines in the drawings showing portions of the battery are included for the purpose of illustrating environmental structure and form no part of the claimed design.

1 Claim, 11 Drawing Sheets
